MOVABLE ROOF DRAINAGE SYSTEM
Charles E. Johnson, Buffalo, N.Y., assignor to Hewitt-
Robins Incorporated, Stamford, Conn.
Filed June 1, 1962, Ser. No. 199,499
4 Claims. (Cl. 220—26)

This invention pertains to apparatus for draining water from movable roof storage tanks. Many storage tanks, for large volumes of liquid have a movable roof. The roof floats upon the surface of the liquid or is otherwise supported so that it rises and falls in accordance with the level of the liquid in the tank. These roofs move up and down within the walls of the tank. It is necessary that a means be provided for drainage of the roof while the roof is within the tank. It is well known to provide some sort of conduit connected to the center of the roof, to pitch the roof toward the center, and run the conduit through the tank to the exterior. It is necessary, however, in such an arrangement, to have some flexible hose or flexibly connected pipe system extending between the fixed tank structure and the movable roof.

As simple as the problem seems to be, actually difficulty has been experienced in providing suitable means for draining the roof. It is known, for example, to use weighted hoses. These often take the form of a hose in which a lead wire is placed as a form of core. In other instances a chain is used to anchor a hose to the bottom of the tank. It is likewise known to use pipes which are pivotally connected by swivel joints. There have also been suggested combinations of pipe and hoses. Where pipes are used, or combination of pipes and hoses are used, there is a maintenance problem with the joints or connections and often leakage will occur and/or improper operation of the joint or flexible section. Where hoses alone are used they will often kink or crack or form air pockets which will interfere with the drainage.

One object of this invention is to provide a simple, yet completely reliable drainage system. A further object is to obtain the advantages of a continuous conduit member extending from the roof to the exterior of the tank.

Yet a further object of this invention is to provide a drainage system having the advantage of a single, continuous hose constituting the flexible means interconnecting the roof and the fixed structure yet wherein the hose will not kink or have air pockets formed in it.

Still a further object of the invention is to provide a drainage system embodying a flexible conduit which will maintain its proper position during all movements of the roof so that drainage will not be interfered with. These and other objects and advantages will become apparent from the following description and the accompanying drawings wherein:

FIGURE 1 is a fragmentary, sectional, elevational view of a tank drainage means constructed in accordance with the invention in association with a tank of the type with which such means can be employed and showing the roof of the tank in its uppermost position.

FIGURE 2 is a view similar to FIGURE 1 but showing the roof having lowered a substantial distance with the tank.

FIGURE 3 is a section along line 3—3 of FIGURE 1.

FIGURE 4 is a section along line 4—4 of FIGURE 1.

FIGURE 5 is a section along line 5—5 of FIGURE 1.

FIGURE 6 is a fragmentary, right elevational view showing a modified form of structure that can be used.

FIGURE 7 is a section taken along line 7—7 of FIGURE 6.

A drainage system for a tank roof, such as illustrated in the drawing, must be effective at all times or water will collect upon the top of the tank. Further, the system must

2

be one by which leakage can be avoided. It is also very desirable that the system be relatively inexpensive, contains relatively few moving parts and be easy to install and maintain.

According to the instant invention there is provided a drainage system embodying a continuous member forming the flexible connection which is seamless, highly flexible and embodies no joint within its length and which can be placed as a unit relatively inexpensively and quickly.

According to the invention there are no rigid members interconnected by flexible joints involving packing etc. which must either be adjusted, repaired or replaced or disconnected for effecting repair or replacement. Instead, as indicated above, when it might become necessary to effect a repair the single conduit member simply disconnected at its ends and a new one placed in position.

Referring now in particular to the drawing, there is shown a storage tank 10. This has a commonly-known floating roof 12. The roof is of an inverse conical shape and at its apex is provided with a drain opening 14 which may be provided with a screen as illustrated. A pipe 20 extends a short distance below the opening which is provided with a fitting 16. At the base of the tank 10 there are provided straps 18 which fix a conduit 20 in the form of the invention illustrated the conduit 20 is a rigid pipe and has a fitting 22 at its inner end. It will be understood that the pipe extends through the side wall of the tank. A flexible hose 24, having two end fittings 26 and 28, is connected to the fittings 16 and 22 respectively and forms a flexible conduit interconnecting the roof drain and the rigid pipe 20. It will be understood that the flexible hose 24 has the usual end fittings which cooperate with the fittings 16 and 22 in the known manner to effect the desired leak-proof connection.

Adjacent the upper fitting 16 a plate-like pivot member 26 is secured to the roof member 12. Arm-like rod 28 has a looped upper end extending through an opening 30 in the plate 26 in a manner such that the arm 28 can freely pivot (see FIGURE 4).

Adjacent its lower end the arm 28 is provided with an enlarged portion 30. This supports an axle 32. A pulley 34 is supported on the axle. The axle and pulley are retained on arm 28 by means of a nut 36. A second arm-like rod 38 having an enlarged end 40 is also pivotally mounted on the axle 32. Arm member 38 extends downwardly from the axle 32 to a point at which it is pivotally connected to the bottom of the tank. Journy-like portion 40 receives an axle 44. A lower pulley 46 is supported on the axle 44 and the axle is mounted in a pair of brackets 48 and 50. A suitable nut 52 is provided to secure the axle in position.

It will be noted that the total length of the two arms and their pivotal interconnection is greater than the distance between the fixed lower pivot and the fixed upper pivot for the two arms when the roof is at its uppermost position (FIGURE 1). Thus the two are in a bowed condition with respect to the roof. Thus when the roof is lowered the central pulley member 34 must move to the left, viewed in FIGURES 1 and 2. The flexible hose member is selected to be of a length such that it will just go over the two pulleys when the roof is in its uppermost position. Thus the hose member, when the roof is raised, assumes the same aspect with respect to the roof and the tank itself as the two arms. Furthermore, it will be apparent that, as illustrated in FIGURE 2, the hose member will likewise stay parallel to the two arm members during movements of the roof. As a result the hose will always provide a downwardly extending conduit with respect to any water entrapped upon the roof. Also, the hose will not kink. Yet it is further apparent that should any

ement of the conduit be necessary it is simply accomplished by disconnection of the two end fittings and substituting of a complete new hose. There are no tight joints which can leak or which may be so tight as to prevent leakage that they will bind. That is, connection between the two links and their connections and supports can be very loose to provide absolute freedom of movement. If two connected pipes were used there were a swivel joint in between, the connection would have to be tight enough to prevent either leakage of water into the fluid or leakage of the fluid out of the

FIGURES 6 and 7 show a slight modification which may be employed if desired. As illustrated, if desired, as such as 54 can be used in association with the pulley to further insure that the hose will remain in proper position.

While a preferred form of the invention has been shown it will be understood by those skilled in the art that changes can be made within the scope of the appended claims, and accordingly I claim an exclusive right to all that come within the scope of the appended claims.

For use as a tank roof drainage connection in a large tank having a movable roof, a pair of arms, means pivotally connecting said arms, a pulley connected to the latter means and pivotal on an axis parallel to that to which said arms are pivotal, means for pivotally connecting one of said arms to a movable roof, means pivotally connecting the other of said arms to a fixed structure, a hose extending along said arms and over said pulley, means for connecting said hose to a roof drain opening adjacent the connection of said one of said arms to a roof, means for connecting said hose to a drain connection adjacent the means for pivotally connecting the other of said arms to a fixed structure.

The apparatus of claim 1 including a second pulley connected to said second arm adjacent the means for connecting the latter arm to said fixed structure, said hose also extending over said second pulley.

A tank drainage apparatus for a movable roof of which has a drain opening in the roof comprising a pair of arms, said arms being pivotally connected to each other, a pulley connected to said arms and rotatable about an axis of pivotal connection of said arms to each other, means for connecting one of said arms pivotally to the roof of a tank and means for connecting the other of

said arms pivotally adjacent the base of a tank in such a position that said arms will pivot with respect to each other and with respect to the base and roof about horizontal axes, and in such a position that said arms will have a total length when fully extended with their longitudinal axes parallel greater than the distance between their points of pivotal connection to said roof and adjacent said base, a flexible hose having means at one end for connecting said hose to a drain opening on a roof of a tank at a location adjacent the connection of said one of said arms thereto, said hose having a portion extending from said means of said hose a distance equal to substantially the sum of the lengths of said arms, said portion extending along said arms and over said pulley between said arms so as to be movable therewith during pivotal movement of said arms relative to each other, means connected to the other end of said hose for securing said hose to a drain connection adjacent the bottom of said tank in such a manner that when said arms are connected to the roof and adjacent the base and said means at said one end of said hose is connected to the roof said portion of said hose extends along said arms and over said pulley in substantially fixed relationship with said arms and will move with said arms and pulley while being maintained in connection to the tank and the drain connection and parallel to said arms.

4. The drainage apparatus of claim 3 including, a second pulley member affixed to said other of said arms adjacent the means for connecting said other of said arms to the base of a tank, and the relation between said means connected to said one end of said hose and the means connected to the other end of the hose being such and the length of said portion being such, that said hose portion extends along said arms and over both said pulleys and will be maintained in parallel relationship to said arms and over said pulleys during movement of said arms.
